UNITED STATES PATENT OFFICE.

OLAVES R. MATSON, OF COLUMBUS, WISCONSIN.

TOBACCO PACKER.

Application filed May 23, 1921. Serial No. 472,014.

To all whom it may concern:

Be it known that I, OLAVES R. MATSON, a citizen of the United States, and a resident of Columbus, in the county of Columbia and State of Wisconsin, have invented certain new and useful Improvements in Tobacco Packers, of which the following is a specification.

The present invention relates to a tobacco press or packer and has for its object to provide a device of this character which easily and readily compresses or packs the tobacco into the desired bales or bundles, which is adaptable to efficiently operate upon all varieties of tobacco, which may be readily controlled, and which in general is of simple and durable construction, reliable in operation and easy and inexpensive to manufacture.

Other objects and advantages of the invention reside in certain novel features of construction, combination and arrangement of parts which will be hereinafter more fully described and particularly pointed out in the appended claims, reference being had to the accompanying drawings forming part of this specification, and in which:

Figure 1 is a perspective view of the invention prior to receiving the tobacco, the follower being omitted;

Figure 2 is a view in longitudinal vertical section illustrating the tobacco in the press and under compression;

Figure 3 is an end elevational view, and

Figure 4 is a view in transverse vertical section taken approximately on line 4-4 of Figure 2 and looking in the direction of the arrows, parts being shown in elevation for the sake of illustration.

Figure 5 is a view similar to Figure 4, taken on line 5-5 of Figure 2; and

Figure 6 is a detail perspective view of one of the bifurcated U-shaped arms.

Referring to the drawings wherein for the sake of illustration is shown the preferred embodiment of the invention, the numeral 10 designates generally a frame which includes longitudinally extending side bars 11 and 12, standards 13, 14, 15 and 16 supporting said side bars and end cross bars 17 and 18 connecting the standards 13 and 14 and 15 and 16 respectively.

A press or baling box, designated generally at 20 is carried by the frame and includes side walls 21 and 22, a stationary

end wall 23, a movable end wall 24, a bottom wall 25.

The side wall 21 is stationary and is secured by suitable fastening means to the standards 15 and 16. The stationary end wall 23 is rigidly secured to this stationary side wall and is also fixed to the bottom.

The bottom 25 includes a stationary section 30 rigidly secured in position and a slidable section 31 mounted for longitudinal movement in grooves 32 and 33 defined by the top surfaces of the side bars and the bottom surfaces of the side walls. A metallic bridge plate 34 overlaps the bottom sections 30 and 31, is fixed with respect to the stationary section 30 and permits sliding movement of the section 31 with respect thereto. The side edges of the bridge plate are extended downwardly as at 35 and embrace the side edges of the slidable section 31 in all positions thereby preventing lateral displacement of the same. The slidable section 31 is provided with angle guides 36, each having one leg fixed to the under surface of the sliding section and the other legs slidably engaging the inner surface of the adjacent side bar of the frame. The movable end wall 24 is mounted upon the end of the bottom section 31 and partakes of its movement. Vertical guides 37 are fixed to the movable end wall 24 and cooperate with the side walls of the press box to constrain the end wall to its proper movement. Preferably, the vertical guides 37 are connected with the angle guides 36 so as to coat therewith in the guiding of the movable bottom section and the movable end wall and they may for this purpose be constructed from a single blank of metal.

The side wall 22 includes a swinging section 22^a which is secured to movable sections 14^a and 15^a of the standards 14 and 15, these movable sections being hinged to the lower stationary section 14^b and 15^b of these standards by means of hinges 40. When the section 22^a is swung downwardly it facilitates the placing of the tobacco in or the withdrawal of the tobacco from the press, and when it is swung upwardly in closed position it completes the press box. Means are provided for releasably securing the swinging section in closed position and includes pivoted latch bars 41 and 42 pivoted, as at 43 and 44 upon the standard 13 and stationary end wall 23, respectively and

cooperable with keepers 45 carried upon the standards 14 and 15, respectively.

The side walls 21 and 22 are provided at their upper ends with movable extensions, 5 designated at 47 and 48, the extensions being carried by pivoted arms 49 and 50. Pivoted lock bars 51 and 52 are carried by the extensions 47 and 48 and are engageable with the adjacent side wall to releasably maintain the 10 extensions in cooperative relation with respect to the side walls. It is obvious that when the extensions are maintained in position by the pivoted lock bars that they enlarge the capacity of the press box and retain a larger supply of tobacco or other material therein and that when the lock arms are swung out of engagement with the side walls and the extension released they may be 15 swung downwardly and out of the way.

20 A follower 55 is provided, and is arranged upon the top of the tobacco or other material to be pressed. Means is provided for applying pressure to the follower and includes a stationary unit, designated generally at 56 and a movable unit designated generally at 57. The stationary unit includes a rack bar 58 mounted for rectilinear movement in a slide bearing 59 fixed to the outer side of the stationary end wall 23 and to adjacent portions of the frame. A bifurcated U-shaped arm 60 is pivoted, as at 61, to the upper end of the rack 58 and carries at its other end a cross head 62 engageable with the follower 55. The movable unit includes a rack 64 25 mounted for rectilinear movement in the slide bearing 65 fixed to the movable end wall 24 and a bifurcated arm 66 pivoted, as at 67, to the upper end of the rack and carrying a cross head 68 engageable with the follower at the end thereof opposite the cross head 62.

30

35

40

45

50

Operating mechanism is provided for the stationary and movable units and includes a square shaft 70 rotatably mounted in suitable bearings provided therefor in the main frame and extending from end to end thereof. The rotatable shaft 70 has fixed thereto at one end a pinion 71 meshed with the rack 58 and has splined thereon at the opposite end a pinion 72 which is meshed with the rack 64.

55 A carrier 75 is slidably mounted on a track 76 and coacts with the movable end wall carrying the movable unit. For this purpose the lower end of the slide bearing 65 is fixed to the carrier 75, as at 77, and a strap 78 has its lower end secured, as at 79, to the carrier. The strap 78 has an opening 80 which slidably receives the rotatable shaft 70, and this strap embraces the pinion 72 and is then secured, as at 81, to the movable end wall. The carrier 77 is also connected with the movable section 31 of the bottom by means of a brace 82.

60 65 An operating lever 85 is pivoted, as at 86,

on a bracket 87 and this lever by means of the connecting rod 88 which is pivotally secured at one end to the lever and at the other end to the movable section of the bottom wall, is adapted to impart movement to the 70 movable end wall and the movable bottom section 31 and to the movable unit and carrier organized with these parts.

A crank arm 90 is connected with one end of the rotatable shaft 70 and constitutes the 75 means whereby this shaft may be turned to actuate the units of the means for applying pressure to the follower.

In practice, the press box is adjusted to the desired size by suitable actuation of the 80 lever 85. This moves the end wall and the bottom 31 and varies the size of the press box, as desired. The bale covering and bands therefor is placed in the press box in the usual manner as indicated in Figure 85 2, and the tobacco is then placed therein and the tips of the leaves thereof overlapping in the usual manner. During this operation, the swinging section 22^a of the side wall may be adjusted as desired as may also the pivoted extensions of the side walls. After the tobacco has been placed in the press box the follower 55 is positioned on the top of the tobacco and the cross heads 62 and 68 are 90 then engaged with the follower as clearly shown in Figure 2. Then when the crank 90 is turned the shaft 70 is rotated and the pinions 71 and 72 carried by the shaft are also turned and as these pinions are engaged with the racks 58 and 64 they move these racks rectilinearly in their slide bearings. This movement of the racks is transmitted by the bifurcated arms to the cross heads and thus pressure is imparted to the follower which in turn transmits the pressure to the 95 tobacco and compresses it into the bale. It is to be noted that the crank 90 is adapted to impart the pressure to the cross head 68 irrespective of the position of the movable end wall for the movable unit is carried thereby and the pinion 72 being splined to the rotatable shaft 70 receives movement therefrom in any position thereon.

100 I claim:

1. In a press of the character described, 115 a frame, a press box carried by the frame and including a stationary side wall, a stationary end wall, a side wall having a swinging section, a movable end wall, and a bottom including a stationary section, a movable section, and a bridge plate carried by the movable section, and overlapping the movable section, a follower, means for applying pressure to said follower comprising a stationary unit carried by the 120 stationary end wall and including a slide bearing, a rack mounted therein, a bifurcated arm pivoted to the rack and a cross head carried by the bifurcated arm, a movable unit carried by the 125 mov-

130

- able end wall and including a slide bearing carried by the movable end wall, a rack mounted in said slide bearing, a bifurcated arm pivoted to the upper end 5 of said pivoted rack, and a cross head carried by said bifurcated arm, operating mechanism for the units including a rotatable shaft, a pinion fixed to the shaft and engageable with the rack of the stationary unit, a pinion splined to the shaft and engageable with the rack of the movable unit, tracks arranged on the frame, a carrier 10 slidably mounted on said tracks and carrying the lower end of the slide bearing of the movable unit, a strap having one end fixed to the carrier and having an aperture slidably receiving the rotatable shaft, said strap embracing the pinion of the movable unit and having its other end secured to the movable end wall, a brace connecting 15 said carrier and the movable bottom section, and means for operating said movable end wall.
2. In a press of the character described, 25 a frame, a press box carried by the frame and including a movable end wall, a follower, means for applying pressure to said follower comprising a stationary unit including a rack, and a movable unit carried 30 by the movable end wall and including a rack, common operating mechanism for the units including a rotatable shaft, a pinion fixed to the shaft and engageable with the rack of the stationary unit, a pinion 35 splined with the shaft and engageable with the rack of the movable unit, and a crank for operating said shaft, and means for operating the movable end wall.
3. In a press of the character described, 40 a frame, a press box carried by the frame and including a movable end wall, a follower, means for applying pressure to said follower comprising a stationary unit and a movable unit carried by the movable end 45 wall, common operating mechanism for the units, and means for moving said movable end wall.
4. In a press of the character described, 50 a frame, a press box carried by the frame and including a movable end wall, a follower, means for applying pressure to said follower comprising a stationary unit including a rack, and a movable unit carried by the movable end wall and including a rack, 55 common operating mechanism for the units including a rotatable shaft, a pinion fixed to the shaft and engageable with the rack of the stationary unit, a pinion splined with the shaft and engageable with the rack of the movable unit, and a crank for operating 60 said shaft.
5. In a press of the character described, a follower, and means for applying pressure to the follower including a slide bearing, a 65 rack mounted in said slide bearing, a bifurcated arm pivoted to the rack and a cross head carried by the free end of the bifurcated arm and engageable with the follower, and operating mechanism including a rotatable shaft and a pinion carried 70 by the shaft and engageable with the rack.
6. In a press of the character described, 75 a follower, and means for applying pressure to the follower including a slide bearing, a rack mounted in said slide bearing, a bifurcated arm pivoted to the rack, and a cross head carried by the free end of the bifurcated arm and engageable with the follower.
7. In a press of the character described, 80 a follower, means for applying pressure to the follower including a slide bearing, a rack mounted in said slide bearing, and operating mechanism including a pinion engageable with the rack.
8. In a press of the character described, 85 a follower, and means for applying pressure to the follower comprising a stationary unit including a rack, a cross head connected with the rack and engageable with the follower and a movable unit including a rack and a cross head engageable with the rack and movable with the follower.
9. In a press of the character described, 90 a follower, means for applying pressure to the follower comprising a stationary unit including a rack and a cross head connected with the rack and engageable with the follower, a movable unit including a rack and a cross head engageable with the rack 95 and the follower, and common operating means engageable with said units, including a shaft, a pinion fixed to the shaft and engageable with the rack of the movable unit, and a pinion splined to the shaft and engageable with the rack of the movable unit.
10. In a press of the character described, 100 a frame, a press box carried by the frame and including a movable end wall and a bottom wall having a movable section, a follower operable in said press box, means for applying pressure to said follower comprising a stationary unit including a rack, a cross head connected with the rack and engageable with the follower, and a movable unit carried by the movable end wall and including a rack and a cross head movable with the rack and engageable with the follower, 105 common operating mechanism for the units including a rotatable shaft, a pinion fixed to the shaft and engageable with the rack of the stationary unit, and a pinion splined to the shaft and engageable with the rack of the movable unit, tracks arranged on the frame, 110 and a carrier slidably mounted on the tracks and carrying the movable end wall, bottom section and unit.
11. In a press of the character described, 115 a frame, a press box carried by the frame 120 and including a movable end wall and a bottom wall having a movable section, a follower operable in said press box, means for applying pressure to said follower comprising a stationary unit including a rack, a cross head connected with the rack and engageable with the follower, and a movable unit carried by the movable end wall and including a rack and a cross head movable with the rack and engageable with the follower, common operating mechanism for the units including a rotatable shaft, a pinion fixed to the shaft and engageable with the rack of the stationary unit, and a pinion splined to the shaft and engageable with the rack of the movable unit, tracks arranged on the frame, 125 and a carrier slidably mounted on the tracks and carrying the movable end wall, bottom section and unit.
12. In a press of the character described, 130 a frame, a press box carried by the frame

and including a stationary side wall, a stationary end wall, a side wall having a swinging section, a movable end wall, and a bottom including a stationary section, a movable section, a bridge plate carried by the movable section and overlapping the movable section, a follower, and means for applying pressure to said follower.

12. In a press of the character described, 10 a frame, a press box carried by the frame and including a stationary side wall, a stationary end wall, a side wall having a swinging section, a movable end wall, and a bottom including a stationary section, a movable section, and a bridge plate carried by the movable section and overlapping the movable section.

13. In a press of the character described, a frame, a press box carried by the frame 20 and including a movable end wall and a bottom having a movable section connected with the movable end wall, tracks arranged on the frame, a carrier slidably mounted on the tracks and connected with the movable end 25 wall, and a brace connecting the carrier and the movable bottom section.

14. In a press of the character described, a frame, a press box carried by the frame and including a movable end wall and a bottom 30 having a movable section connected with the movable end wall, a follower, means for applying pressure to the follower comprising a stationary unit and a movable unit carried by the movable end wall, including a slide bearing and a rack mounted therein, operating mechanism for the units including a shaft and a pinion splined to the shaft and engageable with the rack of the movable unit, tracks arranged on the frame, a carrier 35 slidably mounted on the tracks and connected to the lower end of the slide bearing of the movable unit, a strap having one end fixed to the carrier and having an opening slidably receiving the pinion of the movable unit and having its other end secured to the movable end wall, and a brace connecting 40 said carrier and the movable bottom section.

15. In a press of the character described, 45 a frame, a press box carried by the frame and including side walls, a stationary end

wall, a movable end wall, and a bottom wall having a movable section connected with the movable end wall, and guides for said movable end wall and said movable bottom section.

55

16. In a press of the character described, a frame, a press box carried by the frame and including side walls, a stationary end wall, a movable end wall, and a bottom wall having a movable section connected with the movable end wall, and means for operating 60 said movable end wall and said movable bottom section including an operating lever and a connecting rod between said operating lever and said movable section.

65

17. In a press of the character described, a frame, a press box carried by the frame and including a movable end wall, a bottom wall having a movable section connected with the movable end wall, a follower, and 70 means for applying pressure to said follower including a movable unit carried by the movable end wall.

18. In a press of the character described, a frame, a press box carried by the frame 75 and including a movable end wall and a bottom having a movable section connected with the movable end wall, tracks arranged on the frame, and a carrier slidably mounted on the tracks and connected with the movable end wall.

80

19. In a press of the character described, a press box including a stationary side wall, a stationary end wall, a side wall having a swinging section, a movable end wall and 85 a bottom including a stationary section, a movable section connected with the movable end wall, and a bridge plate carried by the movable section overlapping the stationary section.

90

20. In a press of the character described, a press box including a stationary end wall and a movable end wall, a follower, means for applying pressure to said follower including a stationary unit carried by the stationary end wall, and a movable unit carried by the movable end wall, and operating mechanism for said units.
